UNITED STATES PATENT OFFICE.

BAGSTER ROADS SEABROOK, OF WINNIPEG, MANITOBA, CANADA, ASSIGNOR TO
MELVILLE W. MIX, OF MISHAWAKA, INDIANA.

RECORDING-HORN.

1,358,883.

Specification of Letters Patent. Patented Nov. 16, 1920.

Application filed May 2, 1919. Serial No. 294,293.

To all whom it may concern:

Be it known that I, BAGSTER ROADS SEABROOK, of the city of Winnipeg, in the Province of Manitoba, Canada, have invented 5 certain new and useful Improvements in Recording-Horns, of which the following is the specification.

The invention relates to improvements in recording horns particularly as used when 10 making talking machine records and the general object of the invention is to provide an improved type of horn which will receive the sound waves and deliver the sound in a full, clear, pure and natural manner 15 and without muffling or choking the same.

A further object of my invention is to provide a recording horn which, for mechanical reasons may be formed with layers of 20 different materials, but I do not limit myself to any specific order or number of such layers as the important results secured by my invention do not depend specifically on these features but broadly on the use of an inert composition which forms the wall of 25 the horn, of varying thickness, being thinnest at the delivery end and thickest at the receiving end. In this way there is secured a faithfulness of recording that is not otherwise attainable.

30 With the above more important objects in view the invention consists essentially in the arrangement and construction of parts hereinafter more particularly described and later pointed out in the appended claims, 35 reference being had to the accompanying drawing in which:—

Figure 1 represents a longitudinal sectional view centrally through my recording horn.

40 Fig. 2 represents an enlarged partial sectional view through the horn, the section being taken at X—X' Fig. 1.

Fig. 3 represents an enlarged partial sectional view through the horn, the section 45 being taken at Y—Y' Fig. 1.

In the drawing like characters of reference indicate corresponding parts in the several figures.

The horn indicated generally by the reference numeral 1 comprises a flaring body 50 part 2 and an outlet tube 3 continuous with the body part and which may be axially aligned therewith. 4 represents the receiving end of the horn and 5 the delivery end.

55 By observation it will be seen that the wall

of the horn is comparatively thick at the receiving end and tapers gradually to a considerably decreased thickness at the delivery end and the wall of the tube may be of constant thickness and continuous with 60 the body of the horn.

As instanced herein, the horn may be formed of a supporting shell 6 of paper or other porous material on which is placed a non-absorbent and non-responsive composition 9, 11 and 13 whose mass is disposed in reverse manner to that found in certain reproducing horns which are made the subject of separate applications, Serial Number 240,475 of June 17, 1918 and Serial Number 70 255,799 of September 26, 1918.

In adapting the exemplification herein shown I may first shape the paper like shell 6 to the desired form and then impregnate it with a self setting solution to fill the pores 75 so that on hardening the shell becomes quite stiff. Thereafter I may apply layers of fabric 7 and 8. The fabric is moistened by any suitable adhesive which upon drying causes the fabric to shrink and become securely adherent to the shell, thus forming 80 a medium on which the composition is applied. Another layer of fabric 10 may be placed inside of the outer composition for strengthening purposes if the same should 85 be required for any special reasons.

If desired a final finishing coating of varnish 12 may be applied on the outside of the horn. Under certain conditions I may also place some of the composition on the 90 interior of the shell 6, as at 13, and in addition may also apply a coat of varnish 14 on the inside, but neither the inside or outside 95 coatings of varnish, shellac or other medium is basically necessary, in so far as true tone transference is concerned. This latter characteristic in its broadest aspect depends on the increase of mass of non-absorbent and non-vibrant composition wherever the mechanical structure of the horn would make 100 its own vibration periods sympathetically responsive to passing wave trains.

I do not limit myself to the use of a tubular terminus 3 which is shown of uniform diameter and which is joined to the small 105 end of the tapering horn itself. This delivery end may be varied almost indefinitely to suit any requirements which actual practice may demand.

By applying the composition heavier at 110

the receiving end 4 where the initial impact of the sound waves per unit area is greater than at the delivery end 5 I am enabled to build up a horn which lends itself to more truthful recording than is possible when horns are made of non-vibratory material only without disposing the mass of material in relation to the energy factor of the sounds that are to be recorded.

10 The mass of inert composition which is gradually reduced in thickness from end to end of the horn produces a certain intensity of record which may be modified by varying the gradation of the mass from a uniform thickness of wall to a variable reduction according to the practical demands of different subjects. As already stated the use of various layers of fabric and the coatings of varnish are quite immaterial be- 15 cause the invention in its broadest phase resides in a selective disposition of the mass of self-setting and self-hardening composition of which the entire horn may be formed without any extraneous supporting 20 material, as the shell 6, whatever. In such an event dependence can be placed on the rigidity of the composition alone to withstand the usual mechanical stresses to which horns of this type may be subjected.

25

What I claim as my invention is:— 30

1. In recording horns for sounds, etc., a flaring body having openings at opposite ends of different sizes, the thickness of the wall at the larger opening being greater than at the smaller end. 35

2. A recording horn having a tapering body whose wall is thick at the large end and relatively thin at the small end.

3. A recording horn formed of an inert non-absorbent and non-resonant composition large and thick at one end and small and thinner at the other end. 40

4. A conical shaped recording horn having tapering variable thickness walls that are thickest at the large end and thinner at the small end. 45

5. In recording horns, a tapering body of non-absorbent and non-vibrant composition whose inside and outside surfaces are formed at divergent angles with respect to each other so as to converge toward the smaller end of the horn. 50

Signed at Winnipeg, this 26 day of April, 1919.

BAGSTER ROADS SEABROOK.
